UNITED STATES PATENT OFFICE

2,397,500

BARREL CLOSURE

Herman Merker and Howard L. Newton, Milwaukee, Wis., assignors to Pressed Steel Tank Company, Milwaukee, Wis., a corporation of Wisconsin

Application July 25, 1942; Serial No. 452,281

5 Claims. (Cl. 285—39)

This invention relates to improvements in containers, especially designed and adapted for use with beer or other carbonated beverages, and is in the nature of an improvement on the invention described and claimed in United States Letters Patent 2,293,943 issued to us on August 25, 1942, for Container.

In containers of this character, the container or barrel has a single opening through which it is pitched, cleaned, filled, and tapped. A fitting is provided which makes it practical to quickly close the barrel immediately after it is filled with beer (and the nozzle of the racking arm, or the racking machine, removed) so as to avoid foaming and prevent loss of beer. Thereafter the fitting is closed and sealed so as to provide a closed package which cannot accidentally become opened and yet may be readily tapped at the point of use in the ordinary manner. Furthermore, when the barrel is to be refilled, the fitting may be readily removed.

The object of the present invention is to simplify the construction of a device of this kind which is so constituted as to facilitate its assembly and disassembly, and at the same time to insure a reliable, as well as a hermetic, seal when the parts are assembled.

Another object of the invention is to provide a device of this character and having these advantages and wherein the various elements that go to make up the fitting are all united so that they may not separate one from the other and are not likely to be dropped or lost.

Other objects and advantages reside in certain novel features of the construction, arrangement, and combination of parts which will be herein-after more fully described and particularly pointed out in the appended claims, reference being had to the accompanying drawing forming a part of this specification, and in which:

Figure 1 is a fragmentary view in transverse, vertical cross section taken on line 1—1 of Figure 2 and illustrating one embodiment of the invention.

Figure 2 is a fragmentary view in top plan further illustrating the construction shown in Figure 1.

Figure 3 is a fragmentary view in transverse vertical section taken on line 3—3 of Figure 4 and showing a modified form of the invention; and

Figure 4 is a fragmentary view in top plan further illustrating the form of the invention shown in Figure 3.

Referring to the drawing, it will be seen that 55 In the form of the invention shown in Figures

in both embodiments of the invention a beer barrel is provided, but only a fragment of the barrel, designated as 1, is illustrated. While the barrel may be constructed in any suitable way, it is 5 preferably made up in the manner shown and described in our patent above referred to. The barrel is provided with a single opening 2 sufficiently large to permit pitching, cleaning, filling, and tapping therethrough.

10 In both embodiments of the invention the opening 2 is equipped with a special fitting structure, designated as a whole at F in Figures 1 and 2, and at F' in Figures 3 and 4.

The fittings F and F' are similar in construction 15 and each includes a barrel fitting 3. Each barrel fitting 3 comprises a short, cylindrical, metal structure rabbeted, as at 4, around its lower end to interfit with the margin of the opening 2. A weld 5 permanently unites each barrel fitting 20 3 to its barrel head and effects a hermetic seal between these parts.

Referring now to Figures 1 and 2, it will be seen that the fitting F also includes a bung bushing 6 constituted of rubber, rubber composition, 25 or similar elastic material. The bung bushing 6 is externally tapered so as to correspond in its formation to the internal taper of the barrel fitting 3.

A tap fitting, designated generally at 10, is 30 provided and includes a tubular body portion 11, having the usual out-turned flange 12, designed to coat with a standard tap (not shown). A frusto-conical flange 13 is integral with and depends from the tubular body portion 11 and is 35 imbedded in the bung bushing 6, the bung bushing 6 being vulcanized thereto. In this form of the invention the tubular body portion 11 of the tap fitting is surrounded by a cup-like member 14, which may be integral with the body portion of 40 the tap fitting. The bore or opening through the tubular body portion of the tap fitting is closed by means of the usual cork or plug 15.

With this construction, after the barrel is filled 45 with beer, the bung bushing and tap fitting assembly may be quickly introduced into the bore of the barrel fitting to prevent foaming or loss of beer. After it is initially inserted, it then may be driven home so as to provide not only a hermetic seal, but a secure interconnection with the 50 bung bushing 6 and barrel fitting 3. When it is driven home, the bung bushing 6 is tightly compressed and the adhesion between it and the barrel fitting supplies a force to hold the parts assembled.

3 and 4, an elastic bung bushing, designated generally at 20, is provided as before. The tap fitting, designated at 21, has the tubular body portion 22 equipped at its upper end with an outturned flange 23 designed to interfit or coact with the standard tap. A somewhat shorter depending frusto-conical flange 24 is provided and it is embedded in and vulcanized to the bung bushing 20 as before. However, in this formation of the invention, the cup-like member is omitted. Obviously, the structure shown in Figures 3 and 4 may be assembled with the barrel fitting and disassembled therefrom in the manner previously described in connection with the embodiment shown in Figures 1 and 2.

While we have shown and described several constructions in which the invention may be advantageously embodied, it is to be understood that the constructions shown have been selected merely for the purpose of illustration or example and that various changes in the size, shape, and arrangement of the parts may be made without departing from the spirit of the invention or the scope of the subjoined claims.

We claim:

1. In a closure for an opening in a barrel, a fitting joined to the barrel about the opening therethrough, said fitting having an opening therethrough, a bushing seating in the opening in said barrel fitting, said bushing being formed of resilient material, and a tubular fitting having the lower portion thereof embedded in said bushing and forming a unitary subassembly therewith for quick insertion into and sealing seating in the opening through said barrel fitting, said tubular fitting being adapted to receive a device for tapping the contents of the barrel.

2. In a closure for an opening in a barrel, a fitting joined to the barrel about the opening therethrough, said barrel fitting having an opening therethrough, a bushing seating in sealing engagement in the opening in said barrel fitting, said bushing being formed of resilient material, and a tubular fitting having its lower portion embedded in said bushing and forming a unitary subassembly therewith for quick insertion into the opening through said barrel fitting, said tubular

fitting being adapted to receive a device for tapping the contents of the barrel.

3. In a closure for an opening in a barrel, a fitting attached to the barrel about the opening therethrough, said barrel fitting having an opening therethrough, a bushing seating in sealing position in the opening in said barrel fitting, said bushing being formed of resilient material, and a fitting having a tubular portion and a frusto-conical flange extending therefrom and embedded in said bushing and forming a unitary subassembly therewith for quick insertion into the opening through said barrel fitting, said tubular fitting being adapted to receive a device for tapping the contents of the barrel.

4. In a closure for an opening in the barrel, a fitting attached to the barrel about the opening therethrough, said barrel fitting having an inwardly tapered opening therethrough, a bushing tapered externally to conform with the taper of said barrel fitting an opening for seating therein, said bushing being formed of resilient material, and a tubular tap fitting having a flange extending therefrom and embedded in and vulcanized to said bushing and forming a unitary subassembly therewith for quick insertion into and sealing positioning in the opening through said barrel fitting.

5. In a closure for an opening in the barrel, a fitting attached to the barrel about the opening therethrough, said barrel fitting having an inwardly tapered opening therethrough, a bushing tapered to conform with the taper of said barrel fitting opening for seating therein, said bushing being formed of resilient material, and a second fitting joined to said bushing and forming a unitary subassembly therewith for quick insertion into sealing engagement in the opening through said barrel fitting, said second fitting having a tubular body and a flange about the upper end of the body and defining a cup-shaped space therewith and extending over the portion of said bushing unenclosed by the upper end of said barrel fitting.

HERMAN MERKER.
HOWARD L. NEWTON.
